UNITED STATES PATENT OFFICE.

DAVID LAKE, OF PHILADELPHIA, PENNSYLVANIA, AND LEWIS S. CONLEY,
OF HAMMONTON, NEW JERSEY.

DESIGN FOR A FLAG-HOLDER.

SPECIFICATION forming part of Design No. 29,051, dated July 12, 1898.

Application filed April 30, 1898. Serial No. 679,402. Term of patent 3½ years.

To all whom it may concern:

Be it known that we, DAVID LAKE, of Philadelphia, Pennsylvania, and LEWIS S. CONLEY, of Hammonton, New Jersey, citizens of the 5 United States, have invented a certain new and useful Design for a Flag-Holder for Bicycles, of which the following is a specification.

Our design for a flag-holder for bicycles is 10 clearly illustrated in the accompanying drawing, the figure of which represents the holder in perspective.

The essential feature of the design is the bracket having a representation of a cannon 15 at one end and a socket at the opposite end.

A is a bracket having a perforated portion *a* and a bifurcated portion forming two arms

a' a'. Between these two arms is mounted a cylindrical section B in the form of a cannon and secured to the arms at *b b*. In the portion B is a hole *c*, in which the flagstaff is mounted. 20

We claim—

The design for a flag-holder for bicycles as herein described and as illustrated in the accompanying drawing. 25

In testimony whereof we have signed our names to this specification in the presence of two subscribing witnesses.

DAVID LAKE.
LEWIS S. CONLEY.
